(57) **CLAIM**

The ornamental design for a peritoneal dialysis cycler, as shown and described.

DESCRIPTION

FIG. 1 is a perspective view of a peritoneal dialysis cycler;

FIG. 2 is another perspective view of the cycler of FIG. 1, with a cycler cassette access door open;

FIG. 3 is an opposite perspective view of the cycler of FIG. 1;

FIG. 4 is a front perspective view of the cycler of FIG. 1;

FIG. 5 is an end perspective view of the cycler of FIG. 1; FIG. 6 is another end perspective view of the cycler of FIG. 1; and,

FIG. 7 is a rear perspective view of the cycler of FIG. 1.

The bottom view of the cycler is substantially flat and devoid of surface ornamentation.
